COLLATING MACHINE

William C. Rupp, Parma, Leonard W. Kuttler, Jr.,
Wickliffe, and Lawrence R. Johnson, Cleve-
land, Ohio, assignors to Colators, Inc., Paines-
ville, Ohio, a corporation of Ohio

Application October 7, 1940, Serial No. 360,052

8 Claims. (Cl. 270—58)

This invention relates, as indicated, to collating machines, but has reference more particularly to means for feeding the sheets to such machines.

A primary object of the invention is to provide means for rapidly and effectively feeding sheets from a plurality of stacks of sheets onto the sheet depositing tables of a collating machine.

Another object of the invention is to provide means for automatically elevating the tables of such sheet feeding means when the level of the stacks thereon have fallen below a predetermined point.

Another object of the invention is to provide means for simultaneously creating and breaking the suction in the feed arms of a plurality of sheet feeders.

A further object of the invention is to provide means for selectively discontinuing the feeding of sheets from one or more of the stacks of sheets which are being fed to the collating machine.

A still further object of the invention is to provide means for automatically stopping the operation of the collating machine in the event that no sheets are fed to the machine, or more than one sheet at a time is fed to the machine.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various forms in which the principle of the invention may be used.

In said annexed drawings:

Fig. 1 is a cross-sectional view of a collating machine, showing the sheet-feeding mechanism attached thereto;

Fig. 2 is a fragmentary view, partly in elevation and partly in section, taken along the line 2—2 of Fig. 1;

Fig. 3 is a fragmentary plan view of the sheet feeding mechanism;

Fig. 4 is a fragmentary view of the sheet feeding mechanism;

Fig. 5 is a cross-sectional view, taken on the line 5—5 of Fig. 4;

Fig. 6 is a cross-sectional view taken on the line 6—6 of Fig. 4;

Fig. 7 is a plan view of the suction control valve;

Fig. 8 is a cross-sectional view taken on the line 8—8 of Fig. 7;

Fig. 9 is a fragmentary side elevation of the automatic stop means; and

Fig. 10 is a circuit diagram of the automatic stop means.

Referring more particularly to the drawings, the machine in its essential details is similar to that described in the co-pending application of Frank H. Blythe and Leonard W. Kuttler, Jr., Serial No. 326,950, which is owned by the assignee of the present application, the elements 1, 2, 3 and 4 corresponding to the wires 24, wires 30, pins 12 and gauge plate 33 respectively in said copending application.

The present application is concerned more particularly with the means for feeding the sheets to be collated from a series of automatically elevatable feed tables 5, spaced as described in the aforesaid copending application onto the elements 2, at points which may be termed "sheet depositing stations."

Each table 5 has mounted thereon a stack of sheets S, these sheets being inclined at an angle corresponding to the angle of inclination of the collating table proper, so as to facilitate movement of the lower edges of the sheets toward the gauge plate 4. Depending from the table 5, centrally thereof, is a rack 6, which extends through a bracket 7 extending from the frame 8 of the machine, said rack being in mesh with a pinion 9 (Fig. 2) which is slidably keyed to a shaft 10 journalled in the bracket 7.

The shaft 10 has pinned thereto a clutch part 11, which is normally in clutching engagement with a similar clutch part 12 formed on a worm gear 13 which is loosely journalled on the shaft 10, such clutching engagement being maintained by means of a spring 14 interposed between a collar 15 which is pinned to the shaft 10, and the bracket 7.

The gear 13 is driven by a worm (not shown) which is mounted on the shaft of a small electric motor 16 mounted on the bracket 7, and, in this way, the table 5 is elevated at such times that the height of the stack of sheets on the table has fallen below a predetermined level.

For the purpose of energizing the motor 16 when the height of the stack of sheets on the table has fallen below a predetermined level, mechanism is provided comprising a feeler 17 having a stack contacting arm 18 which is adapted to overlie the lower edge of the uppermost sheet of the stack at intervals when sheets are not being removed therefrom, as shown in dotted lines in Fig. 4 but which is moved to the

position shown in solid lines in this figure to permit removal of sheets from the stack.

The feeler 17 has a portion 19 which is substantially parallel with the arm 18, and another portion 20 which is curved to embrace a stationary rod 21, such rod constraining movement of the feeler to the position shown in solid lines.

The feeler 17 is actuated by means of a rod 22 which extends through the portion 19 of the feeler, the rod being reciprocated once as each sheet is removed from the stack. Immediately prior to the removal of each sheet, the rod 22 moves upwardly, causing a pin 23 which extends from the rod to engage the portion 19 of the feeler and moving the feeler bodily to the position shown in solid lines, thereby permitting the sheet to be removed from the stack. On the down stroke of the rod 22, the rod slides through the portion 19 of the feeler, until a spring 24, attached to the upper end of the rod and which is at all times in contact with the feeler, engages the portion 19 of the feeler, whereupon the feeler is pulled downwardly to the position indicated by the dotted lines. In order to insure that the spring 24 will engage the portion 19 of the feeler upon downward movement of the rod 22, the base 24' of the spring is of greater width than the diameter of the opening in the portion 19 of the feeler through which the rod 22 slides.

When the height of the stack of sheets has fallen to a predetermined level, the portion 19 of the feeler engages a normally open limit switch 25, closing it, and thereby energizing the motor 16, which elevates the table 5, the switch opening automatically after the table has been elevated to the desired degree. The position of the limit switch 25 may be adjusted, a manually-operable rod 26 being provided for this purpose.

It is desirable, at times, to elevate or lower the table 5 manually, and for this purpose the shaft 10 is provided at one end with a hand-wheel 27, permitting the shaft 10 to be pushed downwardly, thereby disengaging the clutch part 11 from the clutch part 12, and permitting the table to be elevated or lowered by merely turning the hand-wheel in the desired direction.

The sheet-feeding mechanism further includes sucker tips 28, mounted on hollow arms 29, there being one of these arms disposed centrally over each stack of sheets, all of the arms being rigidly secured to a tube 30 which extends along the collating machine for substantially the entire length of the latter.

Parallel with the tube 30 is a second tube 31, to which is pivotally secured a lever 32 having portions 33 which are clamped to the tube 30. A rod 34 is pivotally connected to the lever 32, and this rod is pivoted at its lower end to one arm 35 of a bell crank lever, the other arm 36 of which is pivoted as at 37, to the frame of the collating machine. The bell-crank lever carries a cam roller 38, which, due to the action of a spring 39, is normally maintained in engagement with a cam 40, which is secured to the shaft 41 driven by the main driving motor 42 of the machine. As the cam 40 is rotated, the lever 32 is rocked about the tube 31, and in this way the suction arms 29 are rocked towards and away from the stack of sheets.

In addition to this rocking movement of the arms 29, they are at the same time moved bodily towards and away from the collating table. For this purpose, the tube 31 is secured to a bracket 43, which in turn is secured to a post 44. The post 44 is secured to a rock shaft 45 on the frame

of the collating machine, and which is rocked by means of a lever 46. The lever 46 carries a cam roller 47 which is maintained in engagement with a cam 48 on the shaft 41, by means of a spring 49.

The conjoint action of the cams 40 and 48 causes the suction tips 28 to follow a path of movement which is indicated by the dotted lines in Fig. 1, suction being applied to the tips during the movement of the tips toward the right as viewed in this figure, and being cut off during movement of the tips toward the left.

Suction is applied to the arm 29 by means of flexible tubes 49, the tubes of each successive pair of arms being connected to a control valve, the detailed construction of which is shown in Figs. 3, 4, 7 and 8.

The control valve comprises a housing 51 which is secured as by means of a set screw 52 to the upper end of the post 44, which is hollow. The housing 51 is provided with a pair of parallel passageways 53 and 54, each of which is in communication with the interior of the post 44 by means of aligned openings 55 and 56 in the housing and post respectively. Disposed within the passageways 53 and 54 are plungers 57 and 58, each of which has one side cut away as at 59 for a purpose to be presently described. The tubes 49 are connected to nipples 60, which in turn are connected to the housing 51, and communicates with passageways 61 which lead to the passageways 53 and 54.

The plungers 57 and 58 are movable in the passageways 53 and 54, and for the purpose of frictionally holding such plungers in any position to which they are moved, balls 62 are provided, which are pressed inwardly against the plungers by means of springs 63 secured to the housing 51 by means of screws 64.

With the parts, as shown in Fig. 7, and suction applied continuously to the post 44, continuous passageways are provided between the post and each of the tubes 49, such passageways consisting of the openings 56 and 55, the spaces between 45 the walls of the passageways 53 and 54 and the cut-away portions 59 of the plungers, passageways 61 and nipples 60. With the parts thus maintained, suction will be applied to the tips 28, and the sheets carried from the stack 5 to the sheet depositing stations.

When the posts 44 reach their most advanced positions, the reduced ends 65 of the plungers 57 and 58 engage a stationary plate 66, causing the plungers to be moved rearwardly in the housing 51, and the portions 67 thereof to cover the passageways 61, thereby breaking the suction in the tubes 49.

At the termination of the rearward movement of the posts 44, the rear ends of the plungers 57 strike an abutment member 68, thereby restoring the plungers to their initial position, and re-establishing suction in the tubes 49.

It is desirable at times to discontinue the feeding of sheets from one or both of two adjacent stacks, and for this purpose, means are provided for avoiding restoration of one or the other or both of the plungers 57 to a position in which suction is created in the tube 49 which is controlled by such plunger. For this purpose, the abutment member 68, which is mounted on a bracket or arm 69, is provided with openings 70, 71, 72 and 73, each of which is of a size sufficient to receive the rear end of the plunger. The opening 72 is at 90 degrees from the openings 70 and 73, and the opening 71 at 90 degrees from

the openings 70 and 73. A handle 74 extends from the abutment member, so as to enable such member to be rotated to present no opening on its front face, or both openings 70 and 73, or one or the other of the openings 71 and 72.

Means are also provided for automatically stopping the main drive motor 42 of the collating machine, in the event either that no sheets are deposited onto the elements 2 from any stack of sheets, or two sheets are deposited at a time. Such means are best shown in Figs. 1, 9 and 10.

In Fig. 10, reference numeral 42 designates the main drive motor of the collating machine and corresponds to the motor 17 in the aforesaid application of Blythe and Kuttler. This motor is energized by the main lines 75, 76 and 77, which are controlled by a circuit breaker 78. This circuit breaker is hand set and is controlled by a circuit consisting of the lines 79 and 80 from a low voltage source of supply, which lines are controlled by a switch 81 which is normally open, but which may, at times, be closed by moving it downwardly into contact with a grounded contact 82. This closing of the switch 81 is accomplished by means of a micrometer screw 83 which is mounted on a lever 84 which, in turn, is pivoted as at 85 to the gauge plate 4. The lever 84 is pivotally connected to a rod 86 which in turn is connected to a lever 87 pivoted as at 88 to the plate 4. The lever 87 carries a cam roller 89. The screw 83 is normally maintained in its uppermost position by means of a spring 90, so as to permit a sheet to be fed onto the table without striking such screw. When the sheet has been placed on the machine, however, it is desirable to return the screw 83 to a position in which it engages the sheet. For this purpose, a cam 91 is provided which is mounted on a shaft 92, which shaft revolves once each time that a sheet is fed onto the machine. In other words, the cam 91 engages the roller 89 so as to rock the lever 87 and thereby move the contact screw 83 down into engagement with the sheet.

If a single sheet has been properly placed over the switch 81, such sheet will insulate the switch 81 from the screw 83, but the thickness of such sheet will not be sufficient to depress the switch 81 into engagement with the contact 82, so that the machine will continue to run. If no sheet has been placed over the switch 81, the screw 83 will directly contact the switch 81, establishing a circuit through switch 81, screw 83, lever 84, and grounded line 93, thereby deenergizing the motor 42. If two sheets have been placed over the switch 81, the thickness of such sheets will be sufficient to cause the screw 83 to depress the switch 81 into contact with line 82, thereby deenergizing the motor 42.

It is thus seen that the machine will be stopped either when no sheet is supplied to the machine or when more than one sheet is fed to the machine.

It will be understood, of course, that when the suction in either one of the tubes 48 is broken, that the screw 83, which is associated with the feed from the table controlled by such tube, will be elevated sufficiently as to render it ineffective.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. In a collating machine, a plurality of sheet-feeding tables, feeder arms for conveying sheets from each of said tables to said machine, a hollow post for bodily moving said arms, and a single valve mounted on said post, and controlling suction to said arms.

10 2. In a combination with a collating machine, a plurality of sheet-feeding tables, feeder arms for conveying sheets from each of said tables to said machine, a hollow post for moving said arms towards and away from said machine, a valve mounted on said post, flexible tubes connecting said valve and arms, and plungers in said valve for controlling communication between said post and each of said arms.

15 3. A valve comprising a housing having a pair of parallel passageways therein, a plunger in each of said passageways, and friction means for maintaining said plungers in selected positions.

20 4. In combination with a collating machine, a plurality of sheet feeding tables, suction feeder arms for conveying sheets from each of said tables to said machine, means operative at substantially the termination of the movement of said feeder arms to said machine for simultaneously breaking the suction in all of said arms, and means operative upon return of said arms to their initial position for restoring the suction in said arms, said last-named means being adjustable to selectively prevent restoration of the suction in one or more of said arms.

25 5. In combination with a collating machine, a plurality of sheet feeding tables, suction feeder arms for conveying sheets from each of said tables to said machine, means operative at substantially the termination of the movement of said feeder arms to said machine for simultaneously breaking the suction in all of said arms, and means operative upon return of said arms to their initial position for restoring the suction in said arms, said last-named means comprising abutment members which are rotatable to selectively prevent restoration of the suction in one or more of said arms.

30 6. In combination with a collating machine, a plurality of sheet feeding tables, suction feeder arms for conveying sheets from each of said tables to said machine, means operative at substantially the termination of the movement of said feeder arms to said machine for simultaneously breaking the suction in all of said arms, and means operative upon return of said arms to their initial position for restoring the suction in said arms, said last named means comprising an abutment member which is rotatable to selectively prevent restoration of the suction in one or more of said arms.

35 7. In combination with a collating machine, a plurality of sheet feeding tables, suction feeder arms for conveying sheets from each of said tables to said machine, a hollow post for bodily moving said arms, and a single valve mounted on said post, said valve having plungers therein for independently controlling communication between said post and each of said arms.

40 8. In a machine of the character described, a hollow post, a control valve secured to said post, said valve comprising a housing provided with a plurality of parallel passageways, each of which is in communication with the interior of said post, and plungers disposed in said passageways.
